UNITED STATES PATENT OFFICE

CHARLES WESLEY ADDY, JOSEPH BILLING, AND HAROLD HALKYARD, OF SPONDON,
NEAR DERBY, ENGLAND, ASSIGNEES TO CELANESE CORPORATION OF AMERICA, A
CORPORATION OF DELAWARE

TREATMENT OF YARNS OR THREADS

No Drawing. Application filed August 23, 1926, Serial No. 131,116, and in Great Britain June 4, 1926.

This invention relates to a process of sizing and dressing yarns or threads in general for weaving, warp or circular knitting or other textile purposes, and is applicable to yarns composed of or containing natural fibres or cellulose acetate or other artificial filaments or fibres.

Hitherto the sizing of yarns has usually been performed on slashing machines or the like, in which lengths of yarn are unwound and passed continuously through a receptacle containing a farinaceous or other paste and then between pressure and clearing rollers to remove excess of size, the yarn being afterwards dried and wound continuously on to a beam or other convenient carrier. Hanks of yarn have also been dipped in a receptacle containing size, squeezed to remove excess of size and afterwards allowed to dry.

These methods of sizing and dressing yarns have a number of drawbacks—for instance the pressure rollers frequently get out of condition for lack of attention—but despite many attempts have not so far been superseded.

According to the present invention, packages of yarn or thread, wound on bobbins, cops, pirns, tubes, spools or similar carriers are immersed in a solution of a sizing or dressing agent (hereinafter termed a sizing agent) in a volatile solvent until they are thoroughly impregnated therewith, the packages of yarn or thread are then removed, and the yarn or thread is dried by evaporation of the solvent and wound continuously on to hanking frames, bobbins or other usual or desired carriers for the sized or dressed yarn or thread.

The drying is conveniently effected during the operation of winding the yarn or thread onto the final carrier, but may also be performed wholly or partly while the yarn is still in its original package and before the winding operation takes place. The yarn or thread may even be allowed to dry slowly on the bobbin or other original carrier, and then be stored and wound off when required.

According to the nature of the sizing or dressing agent, and the rate of drying required, various volatile solvents such for ex-

ample as water, benzene, toluene or xylene may be employed. Mixtures of volatile solvents with other solvents, for instance solvents that volatilize with difficulty, such as paraffin oil, can also be used.

The sizing or dressing agent employed should be capable of forming a coating on the yarn or thread that is free from brittleness and liability to dust off, and at the same time is free from stickiness. Sizing compositions of a suitable character are described and claimed in British Patent Specifications Nos. 244,947 and 244,979, and in the corresponding U. S. specifications S. Nos. 728,799 and 728,800, which disclose a number of mixtures of resins or metallic resinate or naphthenates with non-drying oils, fats, waxes or fatty acids, and also solutions of such mixtures in volatile solvents.

Conveniently the invention may be carried into effect in the following manner. Packages of yarn or thread wound on suitable carriers are placed in a vessel provided with a closure which can be rendered air tight. The vessel is then evacuated and a solution of a sizing or dressing agent of suitable concentration is admitted to the vessel. The penetration of the yarn by the solution may be aided by the application of pressure, or vacuum and pressure may be applied alternately as often as may be necessary to ensure complete impregnation of the package. When the impregnation is complete, the yarn is removed from the vessel and wound off directly on to hanking frames or on to bobbins or other carriers under such conditions that, during the passage of the yarn from the original to the final carrier, the solvent is evaporated, leaving an even layer of the sizing or dressing agent on the yarn.

The evaporation of the solvent may be effected at ordinary room temperature, but if desired or necessary, the yarn or thread may be passed over a hot plate or steam pipes in order to facilitate the evaporation, or may be subjected to the action of currents of air or other gas or vapour aided, if desired, by the application of heat or reduced pressure for the same purpose. The evaporated solvent may be recovered by absorption or condensation by any of the

100

methods commonly employed. As previously stated, the solvent may be wholly or partly evaporated before the package is unwound. Thus, for instance, the packages of yarn or thread may be stored for any desired period in chambers through which a current of warm air may be passed or allowed to circulate, and then, after the evaporation of the solvent has been completed, or has proceeded to any desired extent, the packages of yarn may be removed and wound off on to the final carrier, the evaporation of the solvent being completed when necessary during the winding operation.

15 The amount of size or dressing deposited on the yarn or thread may be varied in accordance with requirements by varying the concentration of the solution used.

What we claim and desire to secure by Letters Patent is:—

20 1. Process for sizing yarn, comprising impregnating yarn while in the form of a package wound on a carrier by immersing the package in a solution of a sizing agent in a volatile solvent, separating the package of impregnated yarn from the excess sizing solution, drying the impregnated yarn by evaporation of the solvent, and winding it continuously on to a carrier for the sized yarn.

25 2. Process for sizing yarn, comprising impregnating yarn while in the form of a package wound on a carrier with a solution of a sizing agent in a volatile solvent, separating the package of impregnated yarn from the excess sizing solution, unwinding the yarn from its original carrier, drying the yarn by evaporation of the solvent, and winding it on to a carrier for the sized yarn, the unwinding, drying and rewinding being effected in a continuous operation.

30 3. Process for sizing yarn, comprising impregnating yarn while in the form of a package wound on a carrier with a solution of a sizing agent in a volatile solvent, exposing the package to conditions permitting the evaporation of solvent, and afterwards unwinding the yarn from its original carrier under conditions permitting evaporation of residual solvent, and winding it on to a carrier for the sized yarn, the unwinding and winding being effected in a continuous operation.

35 4. Process for sizing yarn, comprising impregnating yarn while in the form of a package wound on a carrier with a solution of a sizing agent in a volatile solvent, exposing the package to conditions permitting evaporation of solvent, and afterwards unwinding the yarn from its original carrier and winding it on to a carrier for the sized yarn, the unwinding and winding being effected in a continuous operation.

40 5. Process for sizing yarn, comprising subjecting yarn while in the form of a package wound on a carrier to the action of reduced

pressure, immersing the package while still under reduced pressure in a solution of a sizing agent in a volatile solvent, and, after the yarn has been thoroughly impregnated, separating the package of impregnated yarn from the excess sizing solution, drying it by evaporation of the solvent and winding it continuously on to a carrier for the sized yarn.

45 In testimony whereof we have hereunto subscribed our names.

CHARLES WESLEY ADDY.

JOSEPH BILLING.

HAROLD HALKYARD.
